UNITED STATES PATENT OFFICE.

FREDERICK CHRISTIE, OF PHILADELPHIA, PENNSYLVANIA, ASSIGNOR TO ANNA E. SCHADEWALD, TRADING AS SCHADEWALD MILLS, OF PHILADELPHIA, PENNSYLVANIA.

DESIGN FOR A TEXTILE FABRIC.

Application filed September 27, 1928. Serial No. 28,299. Term of patent 3½ years.

To all whom it may concern:

Be it known that I, FREDERICK CHRISTIE, a citizen of the United States, residing at Philadelphia, in the county of Philadelphia and State of Pennsylvania, have invented a Textile Fabric, of which the following is a specification, reference being had to the accompanying drawing, forming part thereof.

The figure is a plan view of a portion of fabric, showing my new design.

I claim:

The ornamental design for a textile fabric, as shown.

FREDERICK CHRISTIE.
